UNITED STATES PATENT OFFICE.

ALEXANDER C. ESCHWEILER, OF MILWAUKEE, WISCONSIN.

HINGE.

SPECIFICATION forming part of Letters Patent No. 615,690, dated December 13, 1898.

Application filed July 2, 1897. Serial No. 643,251. (No model.)

To all whom it may concern:

Be it known that I, ALEXANDER C. ESCHWEILER, a citizen of the United States, and a resident of Milwaukee, in the county of Milwaukee and State of Wisconsin, have invented certain new and useful Improvements in Hinges; and I do hereby declare that the following is a full, clear, and exact description thereof.

10 My invention has for its object to facilitate manipulation of swing-sash employed in connection with a window-frame having a sill-stool that must be cleared by a direct vertical movement of the sash before the latter can 15 be swung in to open the window; and it consists in certain peculiarities of construction and combination of parts embodied in hinges for said sash, as hereinafter particularly set forth with reference to the accompanying 20 drawings, and subsequently claimed.

Figure 1 of the drawings represents a sectional view of a window-frame and an inside swing-sash connected thereto by means of hinges in accordance with my invention, the 25 sash being in position to close the window; Fig. 2, a horizontal section of a portion of the window frame and sash; Fig. 3, a perspective view of one of the hinges, having its sash-leaf elevated and swung out of normal position; 30 Fig. 4, a similar view of said hinge, having its sash-leaf in normal position; Fig. 5, a horizontal section of the hinge, having its sash-leaf elevated and swung out of normal position; and Fig. 6, a like view of the hinge, having 35 its sash-leaf in normal position.

Referring by letter to the drawings, A represents the head of a window-frame, and B the top rail of an inside sash in swing-hinge connection with a jamb C of said frame, this 40 jamb being provided with a groove with which a stile D of said sash has engagement when the latter is in position to close the window, as shown in Figs. 1 and 2. When the sash is in its normal position, as herein shown, its 45 top rail B comes snug against the head A of the window-frame and the inside of its foot rail is lapped by an ordinary stool F on the sill G of the said frame. Before the sash can be swung to open the window it must have direct vertical lift to clear the sill-stool. Therefore the frame and sash connecting hinges 50 must have their sash-leaves movable in a ver-

tical direction, and clearance for lift of said sash must be had between the top rail of same and the window-frame head, it being preferable to have said sash-rail and frame-head in loose rabbet-joint engagement, as shown in Fig. 1.

Each of the hinges herein shown has its pintle H in rigid connection with a stud projection b at the lower inner corner of the jamb-leaf I thereof, and surmounting this stud projection is a horizontal flange c, having a right-angle notch flanking the inner side of said leaf. The projecting knuckle d of the sash-leaf J has vertical as well as pivotal play on the pintle H and rests on the jamb-leaf flange when in normal position. However, it would be practical to have the pintle H rigid with that portion d of sash-leaf J and loose in that portion b of jamb-leaf I to thus provide for the necessary vertical and pivotal movement of said sash-leaf, this being a mere reversal of what has been previously described; but in either case the upper and lower knobs 75 herein shown are mere ornaments, neither of them being necessarily a part of said pintle, although each is rigid with the stud or knuckle of a leaf. The sash-leaf extends below its knuckle d a distance equal to the thickness 80 of the flange c plus the length of the stud b of the jamb-leaf, and said sash-leaf is also shown as having its lower inner corner of increased thickness due to a foot-lug e, cast therewith. However, it is practical to omit 85 the foot-lug and have less than the full width of the sash-leaf extend below its stud.

In practice the jamb-leaves of the hinges are concealed by the window-casing K, and the other leaves of said hinges are set in the 90 stile D of the sash to stand at right angles to the former leaves when said sash is in normal position with relation to the window-frame.

To open the sash, the same is first lifted until its foot-rail E clears the sill-stool F of the 95 window-frame, the sash-leaves of the hinges being then clear of the notches in the flanges c of the jamb-leaves. This clearance being had the sash is swung inward and supported in more or less open position, the sash-leaves 100 of the hinges having the lower horizontal edges thereof at rest on the flanges c of the jamb-leaves.

When the sash is swung back, it has verti-

cal drop as soon as the sash-leaves of its hinges come into register with the notches in the flanges of the jamb-leaves, and the bottom rail of said sash coming outside of and against the sill-stool F the window will be weather-tight when closed.

Having thus described my invention, what I claim as new, and desire to secure by Letters Patent, is—

- 10. A hinge comprising a jamb-leaf having a lower inner corner projection surmounted by a horizontal flange provided with a right-angle notch flanking the inner side of said leaf, and a sash-leaf in pintle connection with the
- 15. jamb-leaf to have vertical as well as pivotal play, a portion of the sash-leaf being extended

below its projection surrounding the pintle to have engagement with the notch in said flange or ride upon this flange according to the elevation of the latter leaf, it requiring direct vertical lift on the part of said sash-leaf to have the same clear said notch preliminary to an inward swing.

In testimony that I claim the foregoing I have hereunto set my hand, at Milwaukee, in the county of Milwaukee and State of Wisconsin, in the presence of two witnesses:

ALEXANDER C. ESCHWEILER.

Witnesses:

N. E. OLIPHANT,
B. C. ROLOFF.
